CLAIM

The ornamental design for a transparent sauna, as shown and described.

DESCRIPTION

FIG. 1 is a front perspective view of a transparent sauna, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof; and,

FIG. 10 is an enlarged detail view of area 10 in FIG. 1.

The broken lines in the drawings illustrate the portions of the transparent sauna, which form no part of the claimed design. The dash-dot-dash broken lines define the bounds of the enlargements and form no part of the claimed design.
